UNITED STATES PATENT OFFICE

99,334

DESIGN FOR A RADIO RECEIVER CABINET

Alexis de Sakhnoffsky, Philadelphia, Pa., assignor
to Muzak Corporation of Ohio, Lakewood, Ohio,
a corporation of Ohio

Application August 10, 1935, Serial No. 58,060

Term of patent 14 years

To all whom it may concern:

Be it known that I, Alexis de Sakhnoffsky, a subject of the Czarist régime of Russia, residing at Philadelphia, in the county of Philadelphia and State of Pennsylvania, have invented a new, original, and ornamental Design for Radio Receiver Cabinet, of which the following is a specification, reference being had to the accompanying drawings, forming part thereof.

Fig. 1 is a perspective view of a radio receiver cabinet, embodying my design;

Fig. 2 is a top plan view of the structure described in Fig. 1; and

Fig. 3 is a side elevation corresponding to the representation of Fig. 2.

The design resides in the configuration of a radio receiving cabinet having a centrally disposed circular program indicating dial positioned in the upper portion of the cabinet with rounded top portions, and a grille extending beneath the indicating dial as shown in the drawings.

I claim:

The ornamental design for a radio receiver cabinet as shown and described.

ALEXIS DE SAKHNOFFSKY.
